FRANK L. BALLARD, OF ANKENY, AND WILLIAM A. ROBSON, OF SCRANTON, IOWA

MULTIPLE THUMB STALL

Application filed January 11, 1930. Serial No. 420,073.

The principal object of our invention is to provide a thumb or finger stall that has a plurality of selective wearing sides whereby long and efficient use is assured.

5 A further object of the invention is to provide a multiple thumb stall that is easily and quickly placed on the hand of the wearer and when once installed thereon does not accidentally become detached therefrom.

10 A still further object of our invention is to provide a multiple thumb or finger stall that may be quickly changed from the use of one stall to the use of the other stall or from the use of one side of one of the stalls 15 for wearing purposes to the use of the other side of the same stall.

A still further object of this invention is to provide a multiple finger or thumb stall that is made from a single piece of material.

20 A still further object of our invention is to provide a multiple thumb or finger stall that is economical in manufacture and durable in use.

These and other objects will be apparent 25 to those skilled in the art.

Our invention consists in the construction, arrangement, and combination of the various parts of the device, whereby the objects contemplated are attained as hereinafter 30 more fully set forth, pointed out in our claims and illustrated in the accompanying drawings, in which:

Fig. 1, is a side view of our complete invention in one of the many possible positions 35 on the hand of the user.

Fig. 2, is a plan view of our invention showing the opening in its length and through which the hand of the user is placed.

Fig. 3, is a side view of the stall in a folded 40 condition.

Fig. 4, is a cross sectional view of our invention taken on line 4—4 of Fig. 2, and more fully illustrates its construction.

In the performance of many tasks the use 45 of gloves are imperative, and in many instances when gloves are worn, such as in the husking of corn, the principal wearing part of the glove or gloves is the thumb portion. In other words the thumb of the glove rapidly wears out long before the balance of the 50

glove, thereby great economic waste is realized. Single stalls have been used but their useful life is too short. We have overcome all these objections by providing a multiple stall that may be worn with or without gloves 55 and on either the fingers or thumb.

In the drawing we use the numeral 10 to designate the hand of the user having the thumb 11. The stall may be of any flexible material and is made merely by taking an 60 elongated strip, folding its side marginal edges over upon each other and sewing them together and then sewing each end shut in a circular path as shown in Fig. 2. This procedure provides a flat elongated tube rounded 65

at each end and having the two sides 12 and 13 as shown in Fig. 3. Next we cut a longitudinal slot 14 in the centers of each of the sides 12 and 13 which register with each other as shown in Fig. 4. By turning the invention inside out the rough marginal edges 70 will be inside the elongated tube or stall which will not only improve its appearance but adds to its useful life. We have designated the two ends of the elongated tube by the numerals 15 and 16, respectively. Our multiple thumb or finger stall is now completed and ready for use, and all that is necessary to install it upon the hand of the user is to place the fingers and palm of the hand 75

through the slots 14 and place the thumb in between the two slots and into the upper end or upper stall of the invention as shown in Fig. 1. The slots 14 should be of such lengths as to have their lower ends engaging the 80

wrist just back of the palm portion of the hand, thereby yieldingly holding the invention in proper position on the hand. If it is desired a glove may be placed on the hand before or after the invention is placed on the 85 hand of the user in which case the glove will also aid in yieldingly holding the multiple thumb stall in proper position on the hand.

When the forward or inner side of the stall on the thumb begins to show considerable 90 wear the invention should be removed from the hand and the hand inserted through the slots 14 from the opposite direction in order to throw the worn side of the stall to the back of the thumb and the unworn side to the 95 100

front of the thumb. When both sides of this end of the invention become worn the other end of the invention should be used as a thumb stall by rotating the invention one-half revolution on the hand thereby throwing the worn stall or end of the invention below the wrist where it is not used and where it is out of the way. This new unworn end of the stall should also be reversed in due time so that it will also give service on both of its sides. By this construction a multiple stall is provided having four wearable sides, any one of which may be selectively chosen by the user.

If it is desired the stall may be also used on a finger of the hand as well as the thumb or one end of the stall may be placed on the thumb and the other end stall placed on one of the fingers.

When the invention is removed from the hand it may be folded to a flat condition and placed in the pocket of the user where it occupies a minimum amount of space.

Some changes may be made in the construction and arrangement of our improved combination multiple thumb stall without departing from the real spirit and purpose of our invention, and it is our intention to cover by our claims any modified forms of structure or use of mechanical equivalents which may be reasonably included within their scope.

We claim:

1. In a device of the class described, an elongated flexible hollow member closed at both ends, and two longitudinal slots formed in the opposite sides of said elongated member.

2. In a device of the class described, an elongated flexible hollow member inclosed at both ends, and two longitudinal slots in the opposite sides of said elongated member and located near the center of said elongated member.

3. In a device of the class described, an elongated flexible hollow member inclosed at both ends, a longitudinal slot in the side of said elongated member, and a second slot in said elongated member located at a point diametrically opposite from said first mentioned slot.

4. In a device of the class described, an inclosed elongated hollow member having its two ends rounded, and two slots in the opposite sides of said elongated member into and through which the hand may be placed.

FRANK L. BALLARD.
WILLIAM A. ROBSON.
